UNITED STATES PATENT OFFICE.

AXEL UNO SÄRNMARK, OF GOTTFENBORG, SWEDEN.

POROUS MASS.

1,335,200.

Specification of Letters Patent. Patented Mar. 30, 1920.

Application filed April 3, 1919. Serial No. 287,378.

To all whom it may concern:

Be it known that I, AXEL UNO SÄRNMARK, a subject of the King of Sweden, residing at Gottenborg, Sweden, have invented certain 5 new and useful Improvements in Porous Masses, of which the following is a specification.

This invention relates to containers for storing explosive gases and more particularly to the filling or porous mass for such containers and in the accompanying drawing I have shown merely for illustrative purposes two embodiments of this invention wherein:

15 Figure 1 is a longitudinal section of a container filled with a porous mass embodying this invention;

Fig. 2 is a longitudinal section on a much smaller scale of a modified form of container 20 wherein the porous mass is composed of a series of slabs.

Acetylene gas C_2H_2 , is known as an endothermic combination that compressed beyond a certain pressure may easily be disintegrated to its component parts while developing heat to a great extent. This may be of explosive effect. It has been proved by experiment that a wave of explosion either with great difficulty or not at all penetrates through tubes or orifices of small 30 diameter. A porous body may be considered a collection of fine tubes or channels. Therefore in order to store condensed acetylene in steel tubes or tanks without risk these

35 tubes are filled with briquets of porous material, e. g. asbestos, cork, &c. These briquets have been carefully packed in the open tanks and the lids have subsequently been firmly screwed or soldered on. More

40 recently, however, a more suitable and far simpler method has been employed in which whole-rolled tanks are used that are filled with a plastic or pulverized mass, which is afterward allowed to dry in the tank. It

45 has, however proved that when drying such composition may easily fall asunder, when, in the cracks resulting, acetylene accumulates in quantities that endanger explosions. Or perhaps the mass has held during the

50 process of drying, but has not sufficiently withstood blows or jolts afterward.

The present invention avoids all these

drawbacks by employing a plastic mass 1 that can be filled into the tank 2 through a small hole 3, and afterward, without cracking during the drying process, it will prove very durable in every respect. The invention consists in the reinforcing of this mass 1—which may be of any known or suitable composition—by mixing into it 60 loose strands of metal wire, for instance, iron wire. This wire could be cut in various or similar lengths, e. g. 15 to 20 mm., and entire slabs 5, such as are shown in Fig. 2 to fit into the tank 6, could be made of 65 this reinforced mass which in every respect is extremely durable. These slabs could also be placed in the open tanks, the lids 7 being subsequently screwed or soldered on, but herein shown attached by screws 8.

70 Experiments have proved that such a reinforced mass, produced and treated in this manner possesses extreme durability both during the process of drying and, later, as regards jolts during transport, &c.

75 When employing tanks made in one piece with but a single aperture, the mass is inserted through the small hole, after which it is packed and dried. The acetylene intended to be stored in this mass may in the 80 well known manner either be dissolved in acetone or other suitable fluid, or be gaseous. Instead of acetylene any other gas may be stored in the mass made and reinforced according to this invention.

Claims:

1. A porous mass reinforced by short, separated strands of wire distributed therethrough.

2. A filler for explosive fluid containers 90 including a plurality of separately formed bodies each consisting of a porous mass reinforced by the admixture of separated strands of wire distributed throughout said mass.

3. A porous mass reinforced by uniformly distributed, short, loose strands of iron wire.

In testimony whereof I affix my signature in presence of two witnesses.

AXEL UNO SÄRNMARK.
